CLAIM

The ornamental design for a housing for a cellular base unit, as shown and described.

DESCRIPTION

FIG. 1 is a left rear perspective view of a housing for a cellular base unit in accordance with the present invention; FIG. 2 is a left side elevational view of the housing of FIG. 1, the right side elevational view is a symmetrically opposite view;

FIG. 3 is a front elevational view of the housing of FIG. 1; and,

FIG. 4 is a top plan view of the housing of FIG. 1. The broken line showings of FIGS. 1-3 are for illustrative purposes only and form no part of the claimed design.
